SPOOL UNIT FOR ELECTROMAGNETIC
TALKING MACHINESSemi Begun, Berlin, Germany, assignor to C.
Lorenz Aktiengesellschaft, Berlin-Tempelhof,
GermanyApplication March 12, 1935, Serial No. 10,630
In Germany March 10, 1934

4 Claims. (Cl. 242—54)

Electromagnetic talking machines or telephones are known whose spools carrying the sound-recording steel wire or tape are in pairs mounted in a frame or casing, so that each of these sets of spools can be readily replaced by another set.

The sets of spools should be adapted to be stored in a convenient manner, in order that any number of records, each impressed on a wire or 10 tape, may be collected and thus be ready for reproduction at any time. Containers or boxes of special construction have been employed to such end.

The invention avoids the necessity for means 15 of this nature. The arrangement here proposed is cheaper and occupies less place than prior ones.

In the novel arrangement the sets of spools are so constructed that they can be placed one above the other without being liable to become displaced 20 horizontally with respect to each other.

One embodiment of the invention is described hereafter by way of example, reference being had to the accompanying drawing in which

Fig. 1 is a sectional elevation of superposed sets 25 of spools, these sets being constructed in accordance with the invention, Fig. 2 shows a section through this arrangement on the line 2—2 of Fig. 1.

The spools intended to receive the recording 30 wire or tape in a well-known manner are designated A and B. They are rotatably suspended from a frame piece C which in the case shown consists of a plate but may be of any other suitable configuration. The pairs of spools A, B 35 are secured to the frames C by rivet-shaped bodies D having heads E adapted to be received by hollows F of the spools A, B. The recording body is not shown.

When one of the sets of spools is placed on 40 another in the manner seen in Fig. 1, the two heads E of the lower set enter the hollows F of the upper set and then act to prevent the sets from getting displaced horizontally with respect to each other. In this way, any desired number 45 of sets may be stored up without the aid of containers or any other means separate from the sets of spools.

What is claimed is:

1. The combination of two record bearing units for electromagnetic talking machines, each of said units comprising a frame and spools suspended from one side of said frame, the frame of one of said units having projections and the 5 spools of the other of said units having recesses, said projections being adapted to engage said recesses when said two units are placed together and the spools of said second mentioned unit being adapted to contact the frame of said first mentioned unit in a suitable manner whereby by said two units when stacked together are adapted to be held in substantially fixed relationship.

2. A spool unit for electromagnetic talking 15 machines, comprising a set of spools and a plate member adapted to carry said set of spools, said spools being rotatably secured by fastening means to said plate member, a second set of spools provided with recesses, said fastening 20 means extending to the other side of the plate member to engage the spool recesses of said second set of spools when said sets are stacked directly upon each other.

3. The combination of two record bearing units 25 for electromagnetic talking machines, each of said units comprising a frame plate and two spools rotatably suspended from one side of said plate by fastening means extending through said plate, the fastening means of one of said units 30 forming projections on the side of the plate remote from said spools, the spools of the other of said units having recesses at the ends remote from the fastening plate, said projections being adapted to engage said recesses when said two 35 units are placed together.

4. A spool unit for electromagnetic talking machines comprising a set of spools rotatably secured to a frame piece by fastening means extending through said frame piece, said fastening means and said spools forming top nesting portions and bottom nesting portions for said unit, the top nesting portions of said unit being adapted to so engage the bottom nesting of another similar unit when said other unit is 45 placed on top of said first unit that the two units are held against relative motion.

SEMI BEGUN.
